Primary Examiner — Michael A. Pratt*Assistant Examiner* — Wendy L Arminio(57) **CLAIM**

The ornamental design for a wrist band, as shown and described.

DESCRIPTION

FIG. 1 is a front view of a wrist band showing my new design, a rear view being a mirror image thereof;

FIG. 2 is a left side view of the wrist band;

FIG. 3 is a right side view of the wrist band;

FIG. 4 is a top view of the wrist band, a bottom view being identical; and,

FIG. 5 is a top front side perspective view of the wrist band. The broken lines in the drawing figures depict portions of the wrist band that form no part of the claimed design.
